MECHANISM FOR GRINDING MACHINES

Filed July 21, 1947

2 SHEETS—SHEET 2

A technical line drawing of a medical device assembly, labeled "Figure 5" in a vertical box on the left. The assembly consists of a vertical rectangular frame (1) with a horizontal base. A cylindrical component (5) is attached to the top of the frame. A flexible tube (6) connects the cylinder to a U-shaped tube assembly (12) located on the right side of the frame. A curved tube (9) is attached to the bottom of the frame. Various numbered callouts point to specific parts: 2 points to a top bracket; 14 points to a base bracket; 11 points to a base screw; 15 points to a top screw; 12 points to the U-shaped tube; 10 points to a base screw; 8 points to a base screw; 7 points to a base screw; and 13 points to a base screw.

MECHANISM FOR GRINDING MACHINES

Fritz Bernhard Hatzbur, Basel, Switzerland

Application July 21, 1947, Serial No. 762,349
In Switzerland June 22, 1946

2 Claims. (Cl. 51—236)

1

This invention relates to the grinding of work-pieces bounded by surfaces of revolution and in particular to an auxiliary mechanism for machines grinding the work-piece when located between a rotating disk and a suitable rectilinear support. Grinding-machines of this kind may be termed the centreless type, as distinct from machines holding the work-piece rotatably between two spaced points of centrically aligned tools, termed the centre type.

The grinding of the surface of work-pieces, bounded by surfaces of revolution, by machines of the centreless type often lacks precision because the work-piece is not firmly fixed in longitudinal direction, as provided for in the centre type machine.

The present invention has as its main object to provide auxiliary mechanism for the centreless grinding-machine which enables it to additionally fix the work-piece between spaced points of such tools as employed with centre type machines, whereby the work-piece is firmly fixed in longitudinal direction.

Another object of the present invention is to provide a method for removing and fixing the work-piece in a grinding-machine of the centreless type provided with auxiliary mechanism, comprising the steps of raising the work-piece from its grinding position between the control disk and the rectilinear support and subsequently sliding the auxiliary mechanism with the work-piece laterally towards one side of the grinding-machine for manual removal and fixing another work-piece by reversing the sequence of said steps.

A further object of the present invention is to provide said mechanism in such manner as to be capable of being actuated by motor power.

Other objects and advantages will be apparent from the following description when read in connection with the accompanying drawings, in which:

Figures 1 and 4 are cross-sections of a grinding-machine of the centreless type, provided with the new auxiliary mechanism according to my present invention, in working condition;

Figure 2 is a frontal elevational view showing the new auxiliary mechanism in working condition;

Figure 3 is a cross-section of a grinding-machine of the centreless type provided with the new auxiliary mechanism in the raised condition of the work-piece;

Figure 5 is a frontal elevational view, showing the new auxiliary mechanism displaced in axial

2

direction in relation to the control disk and the rectilinear support.

Referring to the drawing by characters of reference, reference numeral 1 designates the base of the rectilinear support of the machine-tool, supporting also the new auxiliary mechanism, 2 is the control disk, 3 the rectilinear support and 4 the grinding disk. The present invention does not pertain to the above items, which are commonly used in grinding-machines of the centreless type for work-pieces bounded by surfaces of revolution.

Reference numeral 5 designates the points on the tool 8, which is supported in a bore at the end of the arm 6. Screws 9 and 10 serve for adjustments of the tools 8. The working-piece 7 is firmly fixed in longitudinal direction between the points 5.

The links 11 are keyed to the shaft 13 and are spaced to support the ends of shaft 12. On the shaft 12, contiguous with the links 11, arms 6 are keyed. Either arm 6 and link 11 on the ends of the shaft 12 are provided with lugs 19, having a pressure spring 18 attached in between, which urges the arm 6 to rotate with the shaft 12. The arms 6 and the links 11 form thus knee joints, so as to raise the tool 8 and the work-piece 7 when moved by rotation of the shaft 13 in counterclockwise direction out of working position. The knee-joint movement is limited by the abutments 16, 17 on the link 6 and the arm 11 respectively.

The shaft 13 is slidably and rotatably supported by the bearings 14, 15. The sliding movement of the shaft 13 is limited by the bearing 15 serving as a stop in regard to the hubs of the links 11. The shaft 13 extends towards the left to co-operate with suitable actuating means (not shown). It is understood, that such actuating means may comprise either manual means or a motor, such as a hydraulic motor.

The work-piece 7 is inserted between the points 5 and firmly set fast by the tool 8. Screws 9 and 10 are provided for the fixing of the tool 8.

Functioning of the auxiliary mechanism is as follows:

For the positioning of the work-piece 7 into the machine-tool the structure formed by the parts 6, 11, 12 and 13 is positioned in relation to the control disk 2 and the rectilinear support 3 as shown in Figure 4. Thereby the holding means, i. e. the points 5 are raised in relation to the working position and laterally moved outside the working position, thereby positioned to readily mount the working-piece 7, provided with centers 20, between the points 5. A rotating and

sliding movement of the shaft 13 is capable to move then the work-piece upon the rectilinear support 3 and contiguous to the control-disk 2 under the effect of the spring 18, and after positioning of the grinding disk, the arrangement is ready for operation. The working piece is vertically supported by the rectilinear support and horizontally fixed in centric position between the points 5. Removal of the work-piece out of its working position after it has been treated, is effected by reversing the sequence of the cited actions for conditioning the work-piece to the working position.

It is claimed and desired to secure by Letters Patent:

1. A grinding-machine for work-pieces bounded by surfaces of revolution, comprising pointed tools firmly fixed in longitudinal direction for holding the work-piece therebetween, a rectilinear support supporting the work-piece in vertical direction in working position, a rotatable control-disk, means for conditioning the work-piece in grinding position and for removing the work-piece after treatment by reversing the movements of said means for conditioning the work-piece in the grinding position and actuating means for said last named means, said means for conditioning the work-piece comprising a slideable and rotatable shaft, links fixed to said shaft, a second shaft pivotally mounted in said links, arms upon said second shaft and spring means cooperating with said arms.

2. A grinding-machine for work-pieces bounded by surfaces of revolution, comprising pointed tools firmly fixed in longitudinal direction for holding the work-piece therebetween, a recti-

linear support supporting the work-piece in vertical direction in working position, a rotatable control-disk, means for conditioning the work-piece in grinding position and for removing the work-piece after treatment by reversing the movements of said means for conditioning the work-piece in the grinding position and actuating means for said last named means, said means for conditioning the work-piece comprising a first shaft, a second shaft, spaced links pivotally connecting said second shaft to said first shaft, arms mounted contiguous to said links, pressure springs cooperating with said arms and abutments upon said arms and links, forming knee joints, the free ends of said arms centrically and adjustably supporting said pointed tools, bearings supporting said first shaft, one of said bearings serving as a stop for the hubs of said links thereby limiting the extent of the sliding movement of said first shaft and said first shaft being slideable and rotatable for moving the work-piece in and out of working position.

FRITZ BERNHARD HATEBUR.
